UNITED STATES PATENT OFFICE

111,182

DESIGN FOR A MULTIPLE LENS METAL GLOBE FOR LANTERNS

Joseph P. McCarthy, Chicago, Ill.

Application August 17, 1937, Serial No. 71,148

Term of patent 3½ years

To all whom it may concern:

Be it known that I, Joseph P. McCarthy, a citizen of the United States, residing at Chicago, in the county of Cook and State of Illinois, have invented a new, original, and ornamental Design for a Multiple Lens Metal Globe for Lanterns, of which the following is a specification, reference being had to the accompanying drawing, forming part thereof.

Fig. 1 is a front elevational view of a multiple lens metal globe for lanterns, showing my new design;

Fig. 2 is a side elevational view; and
Fig. 3 is a top plan view, thereof.

I claim:

The ornamental design for a multiple lens metal globe for lanterns, as shown.

JOSEPH P. McCARTHY.
